UNITED STATES PATENT OFFICE

2,482,950

POST PULLER

Abner S. Toftey, Kanawha, Iowa

Application January 11, 1947, Serial No. 721,617

2 Claims. (Cl. 254—30)

1

This invention relates generally to post puller machines and in particular to a post puller attachment for a farm tractor having a pivoted lifting frame.

An object of this invention is to provide an improved post puller machine.

A further object of this invention is to provide a post puller attachment for a tractor equipped with a lifting frame, which is mountable on the lifting frame at a position providing for its easy movement into a post pulling position and for its complete operation by the tractor operator in a seated position on the tractor.

Another object of this invention is to provide a post puller attachment for a tractor equipped with a lifting frame, which is of a compact and economical construction, readily removed from and assembled with the lifting frame by one man, and efficient in operation to pull posts of varying sizes without requiring any special adjustments.

A feature of this invention is found in the provision of a post puller attachment in which a pair of transverse rock shafts are supported in a longitudinally spaced relation on a frame member, with one of their ends projected laterally from a side of the frame member. A pair of post-engaging arms or jaws oppositely arranged on the rock shafts are mounted for movement between closed positions in a substantially common plane and open positions extended upwardly and inwardly toward each other. The shafts are connected for movement together and are yieldably moved and held in positions at which the jaws are closed. The shafts are manually moved to open the jaws to receive a post between the inner adjacent ends thereof.

Further objects, features and advantages of this invention will become apparent from the following description when taken in connection with the accompanying drawings, in which:

Fig. 1 is a fragmentary perspective view of the rear portion of a tractor showing the post puller attachment of this invention in assembly relation therewith;

Fig. 2 is an enlarged top plan view of the attachment of this invention;

Fig. 3 is an elevational view of the front portion of a tractor showing the attachment of this invention in assembly relation therewith;

Fig. 4 is a plan view of the assembly shown in Fig. 3; and

Fig. 5 is a front view of the assembly shown in Fig. 3.

With reference to the drawings, the post puller attachment of this invention is illustrated in Fig.

1 in assembly relation with a tractor equipped with a pivoted lifting frame, indicated generally at 10, and forming part of a usual Ferguson system. The frame 10 includes a pair of rearwardly extended diverging arms 11 having their front ends pivoted at 12 to opposite sides of a differential housing 13 which constitutes part of a rear axle housing 14. Connected between the rear ends of the members 11 is a transverse drawbar 16. 5 A pair of upright lifting arms 17 have their lower ends pivotally connected at 18 to corresponding ones of the frame members 11, while the upper ends of the lifting arms 17 are operatively connected with a crank member 19, which is rotatably supported in a portion 21 of the tractor. The crank member 19 is operatively associated with lifting mechanism (not shown) for raising and lowering the arms 17.

The post puller attachment (Figs. 1 and 2) includes a body member 22, of a flat bar shape, formed with longitudinally spaced holes 23 adapted for alignment with corresponding holes (not shown) in the drawbar 16. Projected upwardly from the body member 22 is an upright frame 24 comprised of a pair of frame members 26 having lower upright end sections 27 rigidly connected, as by welding, with the body member 22 adjacent the opposite ends of the body member. Each member 26 from its lower section 27, is inclined upwardly and inwardly and then terminates in an upright section 28. The top sections 28, of the frame members 26, are held in a parallel spaced relation by a connecting pin 30. A pin 31 extended between the top sections 28 pivotally supports the rear end 32 of the link 29, while its front end is pivotally connected at 33 with a rocker arm 34, which in turn is pivoted at 36 to the differential housing 13. The rocker arm 34 constitutes part of the usual Ferguson lift system.

Mounted at opposite ends of the frame member 22 and against the inner sides of the lower sections 27 of the upright frame members 26 are transversely extended longitudinally spaced angle members 37 which project laterally outwardly from one side of the body member 22. The angle members 37 are secured, as by welding, to both the top side of the body member 22 and to the inner sides of the frame member sections 27.

Each angle member 37 is provided at its free or projected end with a bearing member 38, and intermediate its ends with a similar bearing member 39. A pair of rock shafts 40 and 41, of a length substantially equal to the angle members 37, are rotatably supported in corresponding pairs of bearing members 38 and 39. Mounted on the

3

rock shafts 40 and 41 at positions between corresponding bearings 38 and 39, so as to be arranged oppositely from each other, are a pair of rock arms or jaws 42, of a flat bar shape, and extended inwardly toward each other. The inner adjacent ends of the jaws 42 are formed with V-shape notches or recesses 43. Extended longitudinally of the jaws 42, and within the recesses 43, are prongs or post-engaging members 44. The jaws 42 are of a length such that when they are moved into closed positions in substantially common plane, their inner adjacent ends are in a spaced relation.

The rock shafts 40 and 41 are connected for movement together by the provision of means including a rock arm 46 mounted on the rock shaft 41 at its end opposite the bearing 38. The corresponding end of the rock shaft 40 carries a rock lever 47 which is reversely inclined relative to the rock arm 46 on the rock shaft 41. A link 48 pivotally connects the free end of the rock arm 46 with the lower end 48 of the rock lever 47. By virtue of this pivotal connection, and the reversed inclination of the rock arm 46 and rock lever 47, the shafts 40 and 41 are connected together for concurrent rotation in opposite directions.

In the assembly of the attachment on the lift frame 10 the body member 22 is mounted on the draw bar 16 such that the angle members 37 are extended rearwardly of the drawbar and in turn of the frame 10.

Bolts 50, inserted through the openings 23, in the body member 22, and corresponding openings in the draw bar 16 secure the attachment with the draw bar. A connecting bar 29 has its forward end pivotally connected at 33 with a rocker arm 34, which in turn is pivoted at 36 on the differential housing 13. As is well known, the rocker arm 34 forms part of the usual Ford-Ferguson system. The rear end 32 of the bar 29 is pivotally supported on a pin 31 carried in the top sections 28 of the frame members 26.

In the operation of the attachment, the post-engaging arms or jaws 42 are normally yieldably moved and held in their closed positions, illustrated in dotted lines in Fig. 1, at which they are in a substantially common plane. This position is maintained by a coil spring 49 connected between the free end of the rock arm 46 and a lateral projection 45 on the body member 22.

When a post is to be pulled, the jaws are moved upwardly to their open positions, shown in full lines in Fig. 1, by the provision of a manually operated cable 51 which is movably supported on the upright frame 24 on a swivel pulley 55 and connected at its end 52 with the upper end 53 of the rock lever 47. It is contemplated that the cable or rope 51 be of a length to provide for its manipulation by the operator of the tractor.

With the jaws 42 manually maintained in their open positions, illustrated in full lines in Fig. 1, and with the frame 10 in a lowered position, the tractor is manipulated to receive the post to be pulled between the inner adjacent ends of the jaws 42. When the post is thus received between the jaws, the rope 51 is released whereby the jaws 42 are moved downwardly toward each other by the action of the spring 49 on the rock shafts 40 and 41. This movement of the jaws 42, by the spring 49, continues until the jaws 42 and members 44 are engaged with the post.

After this initial engagement takes place, the frame 10 is elevated, with this elevation providing for a closing movement of the jaws 42 into locked

4

or embedded positions with the post. After this locking position is reached, the post is pulled on a continued raising of the lift frame 10.

To release the post, after it has been pulled, it is only necessary to lower the frame 10 so that the post on striking the ground moves the jaws 42 toward their full line positions illustrated in Fig. 1.

The post puller attachment, illustrated in Figs. 3-5, inclusive, is similar in all respects in its construction and operation to the attachment in Fig. 1, except for its assembly on a tractor.

Referring to Figs. 3, 4 and 5, the tractor 56 has a lift frame 57 which includes a pair of pivoted lifting arms 58 arranged at opposite sides of the tractor and pivoted at their rear ends on the tractor rear axle (not shown). The arms 58 are raised and lowered by the provision of means including a pair of hydraulic cylinders 59, arranged at opposite sides of the tractor, and connected with the arms 58 by cables 61 which have their inner ends connected to the tractor frame. The cylinders 59 are connected in any usual manner with an oil pump unit (not shown) on the tractor. The forward ends of the lifting arms 58 are connected together by a transverse connecting member 62.

Pivoted lift frames, of the general type described above, are now in common use in tractor loader attachments which usually include a scoop (not shown) generally pivoted at 63 between the front ends of the lifting arms 58.

In the use of the post puller attachment of this invention, the usual scoop for the loader attachment is removed and a frame member 64 having hooked ends 66 is supported on the front ends of the lifting arms 58 and secured thereto by the pivot bolts 63. The frame member 22 is then mounted directly on the frame member 64 and to one side thereof.

The upright frame 24, by virtue of its projecting above the lift frame 57, facilitates the maneuverability of the tractor by the tractor operator, to position the attachment in a post-pulling position.

The operation of the attachment, when mounted on the pivoted lifting frame 57, is similar in all respects to its operation on the pivoted frame 10 in Fig. 1, so that a further description of such operation in connection with Figs. 3, 4 and 5 is believed to be unnecessary.

From a consideration of the above description, it is seen that the invention provides a post puller attachment which is readily assembled with a minimum of time and effort on tractors equipped with different types of pivoted lifting frames. The support of the attachment on the lifting frame does not in any way interfere with a full maneuverability of the tractor for positioning the attachment in a post-pulling position. The attachment is completely operable by the tractor operator to both engage and pull a post, and then to release a post therefrom, so that post pulling operations can be performed in succession and without requiring any dismounting by the tractor operator.

Also, the attachment is adapted to efficiently operate on posts of varying widths without requiring any special adjustments, since the jaws 42 are capable of being wedged in locking positions with a post to be pulled, at any position of the jaws between their full and dotted line positions, illustrated in Fig. 1.

Although the invention has been described with respect to a preferred embodiment thereof,

it is to be understood that it is not to be so limited since changes and modifications can be made therein which are within the full intended scope of this invention, as defined by the appended claims.

I claim:

1. A post puller attachment for a tractor having a pivoted lifting frame pivotally supported at one end on said tractor and having its other end extended outwardly from an end of the tractor, said attachment comprising a transverse body member mounted on said other end of the lifting frame, a pair of transversely spaced rock shafts on said body member extended laterally from one side of said body member, a pair of oppositely arranged post engaging members on said shaft extensions movable inwardly toward each other to positions in a substantially common plane, means connecting said rock shafts for concurrent rockable movement in opposite directions, and means acting on said connecting means to yieldably move and hold said rock shafts in positions at which said post-engaging members are in said substantially common plane.

2. A post puller attachment for a tractor having a pivoted lift frame pivotally supported at one end on said tractor and having its other end extended outwardly from an end of the tractor, said attachment comprising a transverse body member mounted on said other end of the

lift frame, a pair of longitudinally extended rock shafts rockably supported in a spaced relation on said body member, a pair of oppositely arranged post-engaging arms on said shafts, reversely inclined rock arms on said shafts, a link pivotally connected between the free ends of said rock arms, spring means connected between one of said rock arms and said body member for yieldably moving and holding said rock shafts in positions at which said post-engaging arms are in a substantially common plane, and manually operated means for moving said rock shafts against the action of said spring means to provide for the movement of said post-engaging arms to positions inclined upwardly and inwardly toward each other.

ABNER S. TOFTEY.
